(57) **CLAIM**

The ornamental design for a capsule packaging box, as shown and described.

DESCRIPTION

FIG. 1.1 is a front perspective view of a capsule packaging box showing my new design;

FIG. 1.2 is front elevation view thereof;

FIG. 1.3 is a rear elevation view thereof;

FIG. 1.4 is a left side elevation view thereof;

FIG. 1.5 is a right side elevation view thereof;

FIG. 1.6 is a top plan view thereof; and

FIG. 1.7 is a bottom plan view thereof.

The broken lines depict parts of the article that form no part of the claimed design.
